UNITED STATES PATENT OFFICE.

ARTHUR J. MOXHAM, OF JOHNSTOWN, PENNSYLVANIA.

ROLLS FOR ROLLING GIRDER-RAILS.

SPECIFICATION forming part of Letters Patent No. 378,209, dated February 21, 1889.

Application filed December 19, 1887. Serial No. 258,285. (No model.)

To all whom it may concern:

Be it known that I, ARTHUR J. MOXHAM, of Johnstown, in the county of Cambria and State of Pennsylvania, have invented new and useful Rolls for Completing the Rolling of Partially-Finished Blank Forms for Girder-Rails, which invention is fully set forth and illustrated in the following specification and accompanying drawings.

10 The object of this invention is to prepare a blank which can be rolled by special mechanism into two different forms of girder-rail.

The invention will first be described in detail, and then particularly set forth in the 15 claims.

In the accompanying drawings, Figure 1 illustrates in front elevation a pair of roughing-rolls. Fig. 2 illustrates in elevation a pair of finishing-rolls. Fig. 3 illustrates one form 20 of rail which the blank can be subsequently rolled into after it leaves the rolls shown in Fig. 2. Fig. 4 illustrates another form of finished rail which the blank can be subsequently rolled into after it leaves the roll illustrated 25 in Fig. 2. Fig. 5 illustrates the blank as it leaves the last roll-pass, numbered 5 of Fig. 1.

The several figures above mentioned and the several operations pertaining to the invention will now be described as follows:

30 Fig. 1 shows five passes, No. 1 being an ordinary forming-pass, No. 2 an edging-pass, No. 3 a dummy pass, No. 4 an edging-pass, and No. 5 a dummy pass.

Fig. 2 shows passes numbered 6, 7, 8, and 9, 35 all being edging-passes. In all said edging-passes heavy "draft" is maintained on the web portion of the metal forming the rail being rolled, ample room being provided for the spread of metal in order to permit of such draft. In the earlier passes compensation for the "wire-drawing" therein put upon the extreme edges of the lower flanges—which are very wide—and which wire-drawing is excessive, owing to the heavy draft on the center 40 or web portion of the metal being rolled, is effected by the use of the two dummy passes Nos. 3 and 5 above named, more of such passes being preferable, rather than less. It will be observed that the action of these 45 dummy passes is to pinch and spread on the

extreme end of the lower flange of the rails only, as will be seen by comparing the dummy pass No. 5 with the shape of its preceding edge-pass, No. 4, from which rolled metal comes ready for said pass No. 5. The effect of this 55 combination of dummy and edging passes is to produce a thickened center portion of the lower flange of the blank rail, and after the dummy action a thinner edge portion, as illustrated at the points *x x* of Fig. 5; but the inner thick- 60ened portions of said flange are at such points that the tongue of the pass can shape said points with the minimum reduction of the outer points, *x x*, by wire-drawing. By thus reducing the outer edges the action of the tongue of 65 the rolls and these thickened portions is practically to localize or concentrate the work at this point, wire-drawing being thereby reduced. By this means a more rapid reduction of metal is effected. From the last pass, No. 70 9, the blank can be transferred to any desirable grooving-rolls, such as have been lately invented and brought into use; or else grooves can be rolled in the same to complete a section of rail, such as is illustrated in Fig. 3; or 75 other rolling in one or two passes can be effected to complete a finished section, such as is shown in Fig. 4.

I do not limit myself to the exact number or distribution of passes shown, as the number 80 of passes and their distribution into roughing and finishing passes is to a certain extent arbitrary, being influenced by the length and diameter of the rolls, a light train of rolls calling for more passes with lighter draft than a 85 heavy roll train. It is also evident that the rolls can, if desired, be made three-high instead of two-high, as shown.

Having thus fully described my said improvement, as of my invention I claim—

1. Rolls for rolling wide-flanged girder-rails, provided with one or more dummy passes, whose action in said passes is concentrated on the outer or extreme edges of the lower flanges of the rails, substantially as and for the purposes set forth.

2. Rolls for rolling wide-flanged girder-rails, provided with one or more dummy passes, whose action in said passes is concentrated on the outer or extreme edges of the lower flanges 90

of the rails, and with edging-passes, wherein the maximum draft of the rolls is concentrated on the inner and thicker points of said flanges, substantially as and for the purposes set forth.

3. Rolls for rolling wide-flanged girder-rails, provided with passes substantially of the shape

or form shown in the accompanying drawings, and numbered from 1 to 9, inclusive, as and for the purposes set forth.

ARTHUR J. MOXHAM.
